UNITED STATES PATENT OFFICE.

ROBERT A. WEAVER, OF CLEVELAND, OHIO, ASSIGNOR TO THE FERRO ENAMEL SUPPLY COMPANY, OF CLEVELAND, OHIO, A CORPORATION OF OHIO.

BURNING RACK.

Application filed July 21, 1926. Serial No. 123,918.

The invention relates to racks for burning enameled ware and the like, and more particularly to an adjustable rack adapted to accommodate articles of various sizes and shapes.

The usual form of burning rack, such as is in general use, comprises a rigid frame, provided at fixed points with sockets, or the like, to receive tripods, or other supporting means, and owing to the fact that it is necessary to burn enameled articles of varying sizes and shapes, considerable space within the furnace is frequently wasted because of the inability to adjust such burning racks to accommodate the different sizes and shapes of the articles.

The object of the present improvement is to provide a burning rack including a frame having adjustable socket carrying portions to receive the tripods or other article supporting means; and to provide a novel tree with one or more detachable arms for supporting articles to be burnt upon the rack.

The above and other objects may be attained by providing a burning rack comprising spaced bars upon which are slidably mounted cross pieces provided with sockets to receive article supporting means such as tripods, trees and the like; and the improved trees may be of substantially T shape having points or hooks at the ends of the cross bar, the upright of the T being tapered toward the top; and each cross arm is provided with a dovetail socket, being adapted to be detachably secured upon the upright of the T intermediate the ends thereof for supporting additional articles.

An embodiment of the invention is illustrated in the accompanying drawing, in which—

Figure 1 is a perspective view of the improved burning rack;

Fig. 2, an enlarged side elevation of one of the cross pieces;

Fig. 3, a side elevation of one of the improved trees, and

Fig. 4, a plan view of a detachable cross arm for the trees.

Similar numerals refer to similar parts throughout the drawing.

The frame of the improved burning rack comprises the bars 1 and cross pieces 2.

The bars are preferably of triangular cross sectional shape, and bosses 3 are formed up-

on the ends of each cross piece, and provided with triangular openings 4, to slidably receive the bars 1.

The central portion of each cross piece may be enlarged, as shown at 5, and provided with a vertical socket, or slot 6, to receive a shank of the usual tripod, or other article supporting means such as the tree, shown generally at 7.

This improved tree comprises the upright 65 8 preferably of dovetail cross sectional shape and tapered toward the top, the cross bar 9, at the upper end of the upright, being preferably provided with pins or hooks 10 at its ends, upon which articles to be burnt 70 may be hung.

A shoulder 11 is preferably provided at the lower portion of the upright, beneath which is the reduced shank 12 adapted to be received in the socket or slot 6 of the 75 cross piece.

For the purpose of supporting additional articles upon the tree, a detachable cross arm 13 may be provided having at its central portion the tapered dovetailed socket 80 14 adapted to engage the tapered upright 8 and to be slid downward thereon until it is firmly seated in the position shown in Fig. 1.

The cross pieces 2 may be slidably moved 85 to any desired position upon the bars 1, to accommodate the size and shape of the articles to be burnt; and either the usual tripods or other well known article supporting means, or the improved trees may be supported in the sockets of the cross pieces.

Where the trees are used the detachable cross arms may be attached to the uprights where the size and shape of the articles to be burnt will permit of the same, or these arms may be removed in the event that the articles are of such size or shape as to not permit the use of the same.

It will thus be seen that this rack is a 100 considerable improvement over the usual rigid rack which does not permit of any adjustment to accommodate articles of different sizes and shapes, and the improved tree is adaptable for supporting additional articles upon the detachable cross arm, 105 where the size and shape of the articles to be burnt is such as to permit the use of this cross arm.

I claim:

1. A burning rack including spaced bars 110

- and cross pieces slidably mounted upon the bars.
2. A burning rack including spaced bars, cross pieces slidably mounted upon the bars, and article supporting means carried by the cross pieces.
3. A burning rack including spaced bars, cross pieces slidably mounted upon the bars, and article supporting means detachably mounted upon the cross pieces.
4. A burning rack including spaced bars, cross pieces slidably mounted upon the bars and provided with sockets, and article supporting means mounted in said sockets.
- 15 5. A burning rack including spaced, triangular bars and cross pieces having triangular openings at their end portions slidably mounted upon said bars.
6. A burning rack including spaced, triangular bars, cross pieces having triangular
- openings at their end portions slidably mounted upon said bars and article supporting means carried by the cross pieces.
7. A burning rack including a frame provided with a socket and a T-shaped tree 25 having a shank adapted to be mounted in said socket.
8. A burning rack including a frame provided with a socket, a T-shaped tree having a shank adapted to be mounted in said 30 socket and a detachable cross arm adapted to be mounted upon said tree.
9. A burning rack including a T-shaped tree, the upright of which is tapered toward the top and an adjustable arm provided 35 with a tapered socket adapted to be mounted upon said tapered upright.

In testimony that I claim the above, I have hereunto subscribed my name.

ROBERT A. WEAVER.
